US0D1015225S

(12) **United States Design Patent** (10) **Patent No.:** **US D1,015,225 S**
(45) **Date of Patent:** **** Feb. 20, 2024**

(54) **BICYCLE FRAME**

(71) Applicant: **DECATHLON**, Villeneuve d'Ascq (FR)

(72) Inventor: **Baptiste Viry**, Villeneuve d'Ascq (FR)

(73) Assignee: **DECATHLON**, Villeneuve d'Ascq (FR)

(**) Term: **15 Years**

(21) Appl. No.: **29/823,647**

(22) Filed: **Jan. 19, 2022**

(30) **Foreign Application Priority Data**

Jul. 22, 2021 (EM) 008627442-0001

(51) **LOC (14) Cl.** **12-11**

(52) **U.S. Cl.**

USPC **D12/117**

(58) **Field of Classification Search**

USPC D12/107, 111, 114, 117, 126, 159; D21/419, 423, 427, 432, 663, 664, 666, D21/667

(57) **CLAIM**

The ornamental design for a bicycle frame, as shown.

DESCRIPTION

The patent or application file contains at least one drawing executed in color. Copies of this patent or patent application publication with color drawing(s) will be provided by the Office upon request and payment of the necessary fee. FIG. 1 is a perspective view of the bicycle frame showing my new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

1 Claim, 7 Drawing Sheets

(7 of 7 Drawing Sheet(s) Filed in Color)
